UNITED STATES PATENT OFFICE.

WILLIAM F. MERRILL, OF SYRACUSE, NEW YORK, ASSIGNOR TO THE LAMSON COMPANY, OF SYRACUSE, NEW YORK, A CORPORATION OF MASSACHUSETTS.

DETACHABLE CARRIER HEAD.

Application filed February 3, 1926. Serial No. 85,709.

This invention relates to despatch carriers such as are commonly used in pneumatic despatch systems for carrying change between clerks and cashiers in stores, for conveying cards in libraries, and in similar installations.

The carriers ordinarily consist of telescoping tubular shells with bumpers or heads of felt or the like secured to their closed ends. These bumpers or heads have commonly been secured to the tubular shells by bolts, rivets or similar fastening means, and since they are subject to continued wear, their ready replacement has been an item of considerable importance in the upkeep of pneumatic despatch systems. The conventional type of fastening means when used in this location are inaccessible and the removal of the heads from the tubular body portions or shells of the carriers has therefore been a troublesome operation. The present invention relates to improved means provided for quickly attaching or detaching the felt bumpers from the shells of despatch carriers and in the specific aspect disclosed in this application comprises means which may be engaged in locking relation by the rotation of the bumper or head in relation to the shell. The engagement thus provided between these parts is preferably of such a nature that a comparatively firm lock is maintained so that the bumpers upon the ends of the despatch carrier may be used as handles for rotating the telescoping body portions of the carrier relative to each other during their use, as is customary, but so that the bumpers may be detached from the shells by a firm manual rotation, when desired.

In the accompanying drawings, Fig. 1 is a side elevation of a despatch carrier;

Fig. 2 is a detail section on line 2—2 of Fig. 3;

Fig. 3 is a section on line 3—3 of Fig. 1;

Fig. 4 is a similar view showing the parts in a position wherein they may be freely removed from one another;

Fig. 5 is a detail section on line 5—5 of Fig. 7;

Fig. 6 is a section on line 6—6 of Fig. 3;

Fig. 7 is a sectional view corresponding to Fig. 3 and showing a modified form of my invention; and

Fig. 8 is a detail elevational view.

The preferred form of my invention com-

prises a carrier having the telescoping body portions or shells 1 and 2 of conventional form with the bumpers or heads 3 of felt or the like detachably secured to these portions. To this end each head comprises a metal plate 4 and a disc 8 coaxial with but of smaller diameter than the plate 4. A substantially rectangular retainer 9 of resilient metal having depending end portions 12 is secured upon the disc 8. The various parts of the head may preferably be secured together by means of bolts or rivets 13, or the like, having their heads engaging a washer 16 in a central depression in the outer end of the head.

The ends 6 of body portions or shells 1 and 2 of the despatch carrier are formed substantially as shown in Fig. 8, with a central circular opening 7 adapted to receive the disc 8 upon the head and having the extensions 11 shaped to accommodate the ends of the retainer 9. The extensions 11 are arranged at diametrically opposed portions of the opening 7 and provided with bevelled lateral edges 14, and intermediate these extensions are the slots 10 which are adapted to engage the depending ends 12 of the retainer when the head is in locking or operative position (Figs. 3 and 6). The ends 12 also have bevelled edges 19 for facilitating the detachment of the head and shell.

In securing the head or bumper upon a despatch carrier of the type disclosed, the head is applied to the end of the carrier with the retainer 9 registering with the extensions 11 of the opening in the end of the body portion of the container (Fig. 4). The retainer 9 is comparatively resilient and the bevelled surfaces 14 at the lateral edges of the openings 11 help in guiding the depending portions 12 of the retainer up onto the inner surface of the end 6 of the shell.

As the head is rotated the ends of the retainer travel over the inner surface of the end 6 of the shell until finally its depending ends 12 snap into the slots 10 due to its inherent resilience. This resilience is preferably so gauged in relation to the dimensions and disposition of the parts that normal relative rotation of the telescoping body members 1 and 2 may be imparted thereto through the heads 3, but so that the heads 3 may be detached from members 1 or 2 by a firm manual turning of one of these members in relation to the other, the bevelled

edges of slots 10 cooperating with the edges of the retainer to permit such a movement.

Figs. 5 and 7 illustrate a modified form of the invention embodying similar principles of construction. In this form of the invention the end 26 of the tubular member 1 is provided with an opening 7 having extensions 11 similar to those previously described but in place of the slots 10, upstanding and preferably resilient nubs 30 are provided to engage a locking key or retainer 29 secured to a disc 28 which has a thickness substantially corresponding to that of the end 26. With this type of construction the retainer may merely comprise a flat plate cooperating with the resilient nubs 30 for obtaining the locking effect. It is evident that this device may be arranged to be unlocked in relation to the body portion of the carrier with the application of a suitable amount of force in the manner that has been described with reference to the preferred embodiment.

It will now be obvious to those skilled in the art that many optional arrangements of parts are within the purview of this invention, for instance either the disc 8 or plate 4 may be omitted, or integral extensions of such a member may form the retaining means.

I claim:

1. A despatch carrier having a tubular shell with an opening in its end and a detachable head, extensions of said head adapted to lie in the opening in the end of the shell and being movable to a locking position by relative rotation of the shell and the head.
2. A despatch carrier having a tubular shell and a detachable head, resilient projecting means upon said head being adapted to be locked in engagement with said shell by rotation of the head.
3. A despatch carrier having a tubular shell with an end having an opening therein, a head, and resilient projecting retainer means fixed upon said head and adapted to

be inserted in the opening and then to be moved to a locking position by relative rotation of the head and the shell.

4. A despatch carrier having a shell with an opening in the end thereof, a head, an elongate resilient retainer secured upon said head, extensions of the opening in the shell being shaped to register with said retainer and means intermediate the extensions of the opening adapted resiliently to engage portions of the retainer adjacent to its ends to hold the same in locked position when the head is rotated in relation to the shell from a position wherein the extensions of the opening and retainer are registered.

5. A despatch carrier having a shell with openings in the end thereof and a head provided with an elongate resilient retainer having depending end portions, said retainer being fixedly secured to said head, one of the openings in the shell being shaped to register with said retainer, other openings in the end of the shell being adapted to engage the depending ends of said retainer when the head is rotated to move the retainer from its position in registration with the first named opening thereby to hold the head in locked relation with said shell.

6. A despatch carrier comprising a tubular body portion with a central opening in its end having diametrically opposed extensions, a head having a centrally projected portion adapted to register with the central opening in the end of the body portion and an elongate retainer secured upon the central projection and adapted to have its ends received in the extensions of the central opening in the end of the body portion, said head being adapted to be locked to said body portion by the rotation of the head relative to the body portion from a position wherein the retainer has its ends engaged in the extensions of the central opening in the body portion.

Signed by me at Syracuse, New York, this 1st day of February, 1926.

WILLIAM F. MERRILL.
